UNITED STATES PATENT OFFICE

OTTO KRELL, OF BERLIN-DAHLEM, GERMANY

HANGAR FOR AIRSHIPS

Application filed June 30, 1928, Serial No. 289,436, and in Germany April 1, 1927.

The invention relates to improvements in hangars for airships, and more particularly in movable hangars.

The ever growing size of dirigibles makes constantly increasing demands on the apparatus for landing and mooring or housing the dirigibles.

The use of mooring masts adjacent to stationary hangars has various disadvantages, the most salient of which is that the dirigible can only be detached from the mooring mast and run into the hangar when wind and weather are favorable. All the drawbacks of the stationary hangars are at once eliminated by making them movable. The construction of movable hangars whether they are turnable, turnable and at the same time longitudinally and transversely movable or only linearly movable presents, however, increasing technical difficulties, due to the ever increasing sizes of the dirigibles and thus hangars. To overcome these difficulties it is necessary to find new solutions for the construction of such hangars. Particular troubles arise in laying the rails evenly upon which the hangars turn or run. The strains to which the platforms and trucks of the hangars are exposed are very considerable with the vast dimensions of modern hangars, if means are not found to control the forces as regards their magnitude and direction.

One object of my invention is to eliminate these difficulties encountered by movable hangars by providing between the trucks or bogies running upon the rails and the platform of the rotatable or linearly movable hangar hydraulic intermediate members, consisting of cylinders and pistons adapted to reciprocate therein. In order to maintain a constant supporting force, which must correspond at each point of support with the calculations, it is necessary that the supporting pressure apportioned to the individual trucks should be automatically maintained at the same value, when the truck following the rail track is raised or lowered by unevennesses of the track. According to another object of my invention I attain this equal load by connecting all the cylinders of all the trucks with a common storage vessel,

which is maintained at a constant pressure. The rapidity of the pressure equalization between the cylinders may be further increased by also putting the individual cylinders in communication with one another by pressure equalizing pipes. Even if the construction of the hangar should require, that the value of the supporting pressure at individual supporting points deviates from the correct load of the greater number of the supporting points, all truck could nevertheless with their pressure pipes be put in communication with a common storage vessel serving for equalizing the pressure, it being only necessary to choose the diameters of the cylinders and pistons in accordance with the various calculated supporting pressures larger or smaller. When a thus supported hangar is set in motion the trucks follow and adapt themselves to all the unevennesses of the track. The constant hydraulic pressure forces the piston to move in the reverse direction to the cylinder until the truck takes over again the supporting pressure apportioned to it by the calculation. This holds good for the lifting and lowering of the truck. When lifting is to be performed an excess pressure is set up at the truck in question and the piston conveys water under compression into the storage or accumulator vessel. This return feed continues until the ordinary supporting pressure prevails again. The reverse happens when the truck is lowered. In the cylinder is set up a pressure below the normal and water flows into it from the storage tank until the pressure is again equalized.

This system of hydraulic intermediate members has, however, a drawback as long as the pressure equalization can take place unrestrictedly, viz the hangar is in a certain state of equilibrium, which would permit that the hangar takes up any desired oblique position. It would, furthermore, be possible, that when the pressure is exceeded which is necessary for supporting the hangar the play of the hydraulic intermediate members would be eliminated then only when the pistons issue from the cylinders. A further object of my invention is to provide an automatic stroke limiting device between the pressure

pipe and the cylinder. It is, however, not necessary to equip all the pistons with this device, as long as a certain number of pistons are adapted to be controlled, which are preferably located at the edge of the platform or floor of the hangar. These controlled pistons force the own stroke also upon the other uncontrolled pistons, if the supporting pressure absorbed by the controlled pistons forms a sufficient portion of the total pressure. The control process takes place as follows: If a controlled piston reaches the limit of the stroke, which may be adjustable, it shuts itself off from the pressure pipe by means of a stop cock or valve. The chut-off piston no longer participates in the work of lifting the hangar. The non-controlled pistons are thus overloaded, but as the pressure is unable to rise correspondingly because the cylinder is connected with the common storage vessel, the non-controlled piston also comes to rest. The pressure in the common vessel must never drop below the value necessary for carrying the full weight of the hangar.

If for constructive reasons it is necessary to subdivide the hangar transversely to the longitudinal axis, at least three pistons must be provided for each section of the hangar, since three points are necessary to determine the position of a plane.

It will be readily understood that any known or new construction of truck may be used for the purposes of my invention and trucks for one or more lines of rails, as long as the mechanical arrangement is such, that the concentrated pressure exerted by the hanger is uniformly distributed over all the wheels. Since, however, the intercalation of the hydraulic members, the pressure equalization of which is automatically regulated, does in itself not suffice, a further object of my invention is the manner of arranging the pistons and cylinders upon the trucks or the platform of the hangar. According to my invention the pistons as well as the cylinders are journaled in spherical seats. This spherical bearing gives the hydraulic intermediate member in conjunction with the automatic pressure equalization an ideal liberty of motion towards all sides, and the hangar floats, so to say, upon the water under compression.

The fact that in modern hangars for dirigibles, the length of which may amount to several hundred meters and the width 50 meters or more, considerable displacements of the hangar structure in relation to the supporting trucks must be taken into the bargain, makes still further safety measures necessary. The fluctuations in the temperature may already cause considerable alterations in length. It is thus a further object of my invention to render the displacement of the hangar structure transversely to the direction of travel harmless by supporting the hangar upon the pressure cylinders in such a man-

ner, that under all circumstances it is able to move sufficiently far transversely to the direction of travel. Between the cylinder, which in this case is not supported in a spherical seat, and the platform of the hangar rollers or balls are provided for this purpose in order to reduce the resistance to the displacement to a minimum. The piston retains in this case also its spherical seat as supporting point.

In the drawings affixed hereto and forming part of my specification four embodiments of my invention are illustrated by way of example.

In the drawings:

Fig. 1, an elevation, and

Fig. 2, a plan of one embodiment for a single rail truck with hydraulic equalizing member without spherical or ball joints,

Fig. 3, an elevation, and

Fig. 4, a plan of a hangar supported on trucks, in these figures there is also shown the mechanism for regulating the pressure equalization,

Fig. 5, a sectional elevation of a still further truck permitting transverse motion of the hangar,

Fig. 6, a sectional plan of Fig. 5, and

Fig. 7, a sectional plan of a still further modification.

Referring to the drawings H is the hangar for dirigibles, which with its platform rests upon the supporting plate 4, which in its turn carries the cylinder 5 of the hydraulic intermediate member. In the cylinder 5 is adapted to reciprocate the piston 6 connected with the truck. The truck may, as shown in Figs. 1 and 2 of the drawings, consist of four wheels 3 running upon a single rail. The piston 6 as well as the wheels 3 are adapted to oscillate in relation to the frame 7 of the truck. At the piston or at a part participating in the motion of the piston, such as the truck, there is pivoted a lever 8 adapted to operate a two-way cock 1.

In Fig. 1 the two-way cock 1 is in a position which shuts off the flow to the cylinder. This position will be taken up by the cock 1, when the raising of the hangar by the control gear should come to an end. The piston 6 is thus unable to supply any lifting power. If, on the other hand, the hangar descends, the cylinder 5 follows and also the two-way cock indirectly or directly connected with it. The lever 8 pivoted to it then causes a counter-clockwise rotation and liquid is able to pass from the pipe 9 into the cylinder, so that the piston opposes the further descent of the hangar.

A further modification of the truck with an intermediate hydraulic member is illustrated in Figs. 3 and 4 of the drawings. The hangar rests here also by means of the supporting plate 10 upon the hydraulic intermediate member, which consists of the cylinder

11 and the piston 12. The piston 12 rests upon the truck 14, which comprises two four-axle bogies 13 and 13'. In contrast with the first modification illustrated in the Figs. 1 and 2 the equalization of the unevenness of the track is in this case not entrusted to the hydraulic intermediate member alone, but the cylinder 11 as well as the piston 12 is fitted into spherical seats 15 and 15'. The spherical seat 15 is provided in the supporting plate 10 joined to the platform of the hangar, and the seat 15' upon the frame 14 of the truck. By the ball joint all bending strains are kept away from the hydraulic intermediate member. In order to distribute the load uniformly over all the wheels 16 and 16', the frame 14 of the truck is movably arranged on the wheels and axles 13 and 13' by means of the axles 17 and 17' or the bolts or pins 18 and 18'. The truck is entrained by the hangar by means of the hauling bars 19 and 19'.

In very large and long hangars the arrangement of spherical seats will not be sufficient. It is then necessary, already for the purpose of making provisions for expansion and contraction in consequence of temperature fluctuations, to ensure still greater mobility of the platform of the hangar in relation to the trucks. For this purpose the platform of the hangar is adapted to move transversely to the direction of travel upon the hydraulic intermediate members, as shown in Figs. 5 and 6 of the drawings. The cylinder 20 is in this case provided with two arms 21 and 21' extending transversely to the direction of travel. At the ends of the arms are pivoted rollers 23 and 23' by means of axles 22 and 22'. The rollers abut at the top against the supporting plate 24 and 24'. The piston is according to the construction shown in Figs. 3 and 4 supported in the spherical pan 25 in the frame 26. The frame 26 is supported upon the wheels in the same manner as described with reference to the preceding figures. Instead of the rollers balls may equally well be used.

Since the trucks travel on curved or circular rail tracks, particularly in the case of rotatable hangars, it is necessary to render the groups of wheels or their axles 17 and 17' movable around a vertical axis. Such a design is illustrated in Fig. 7 of the drawings. The ends of the frame 14, by means of which the hydraulic support of the hangar rests upon the groups of wheels, are designed as spheres 27 and 27' and the axles are furnished with spherical seats, so that the groups of wheels are capable of swivelling freely around the frame.

By this hydraulic resilient support and by supporting the hydraulic members in spherical seats or on roller or ball bearings the hangar is made indifferent to the unavoidable unevenness in the rail track.

My invention will even permit, that less

care may be bestowed upon the foundations and thus the first costs of the hangar reduced considerably. It is claimed that my invention solves for the first time the problem how to render modern giant hangars rotatable or linearly movable longitudinally or transversely. Movable hangars are, furthermore, an absolute necessity, if it is desired to make the intercontinental communication by dirigibles a safe and thus profitable enterprise, as far as the landing possibilities of the dirigibles are concerned. It is obvious, that the necessity to effect the supply of all the driving means, the picking up and putting down of passengers, and the exchange of worn out or damaged parts by way of the mooring mast would render the punctuality in observing the time tables very doubtful. The use of a mooring mast in conjunction with stationary hangars is only an inferior makeshift and is bound to remain such.

It will be understood that the constructions shown in the drawings are only examples, and that various changes and modifications may be made without going beyond the ambit of my claims.

I claim as my invention:

1. In a rotatable movable hangar for dirigibles, intermediate hydraulic members, consisting of a cylinder with reciprocating piston, inserted between the wheel truck and the supporting plate at the underside of the hangar platform, a hydraulic accumulator (pressure equalizer) in which a constant pressure is maintained, and pipes for connecting all said cylinders with said accumulator and one another.

2. In a rotatable movable hangar for dirigibles, intermediate hydraulic members, consisting of a cylinder with reciprocating piston, inserted between the wheel truck and the supporting plate at the underside of the hangar platform, a hydraulic accumulator (pressure equalizer) in which a constant pressure is maintained, and pipes for connecting all said cylinders with said accumulator and one another, and means for controlling said cylinders and pistons in regard to the supply of the working medium by the vertical motion of said piston or a part connected with it, and thus automatically limiting the stroke of said piston.

3. In a rotatable movable hangar for dirigibles, intermediate hydraulic members, consisting of a cylinder with reciprocating piston, inserted between the wheel truck and the supporting plate at the underside of the hangar platform, a hydraulic accumulator (pressure equalizer) in which a constant pressure is maintained, and pipes for connecting all said cylinders with said accumulator and one another, said cylinder and piston being supported in spherical seats at the platform of the hangar and at the truck.

4. In a rotatable movable hangar for dirigibles,

gibles, intermediate hydraulic members, consisting of a cylinder with reciprocating piston, inserted between the wheel truck and the supporting plate at the underside of the 5 hangar platform, a hydraulic accumulator (pressure equalizer) in which a constant pressure is maintained, and pipes for connecting all said cylinders with said accumulator and one another, said piston being supported in 10 a spherical seat at the truck and said cylinder being adapted to slide at the platform of the hangar transversely to the direction of travel of the hangar.

5. In a rotatable movable hangar for dirigibles, intermediate hydraulic members, consisting of a cylinder with reciprocating piston, inserted between the wheel truck and the supporting plate at the underside of the hangar platform, a hydraulic accumulator 15 (pressure equalizer) in which a constant pressure is maintained, and pipes for connecting all said cylinders with said accumulator and one another, said cylinder and piston being supported in spherical seats at the platform 20 of the hangar and at the truck, and arms upon said intermediate members extending towards both sides beyond the running rails and upon which the platform of the hangar is adapted to rest.

25 6. In a rotatable movable hangar for dirigibles, intermediate hydraulic members, consisting of a cylinder with reciprocating piston, inserted between the wheel truck and the supporting plate at the underside of the 30 hangar platform, a hydraulic accumulator (pressure equalizer) in which a constant pressure is maintained, and pipes for connecting all said cylinders with said accumulator and one another, groups of wheels in said trucks 35 movable around their bolts, spherical ends upon the hydraulic frame (Fig. 7) and correspondingly shaped bearings upon the wheel axle permitting said wheels to turn around a vertical axis.

40 7. In a rotatable movable hangar for dirigibles, intermediate hydraulic members, consisting of a cylinder with reciprocating piston, inserted between the wheel truck and the supporting plate at the underside of the 45 hangar platform, a hydraulic accumulator (pressure equalizer) in which a constant pressure is maintained, and pipes for connecting all said cylinders with said accumulator and one another, said piston being supported in 50 a spherical seat at the truck and said cylinder being adapted to slide at the platform of the hangar transversely to the direction of travel of the hangar, and arms upon said intermediate members extending towards both sides 55 beyond the running rails and upon which the platform of the hangar is adapted to rest.

60 8. In a rotatable movable hangar for dirigibles, intermediate hydraulic members, consisting of a cylinder with reciprocating piston, inserted between the wheel truck and the 65

supporting plate at the underside of the hangar platform, a hydraulic accumulator (pressure equalizer) in which a constant pressure is maintained, and pipes for connecting all said cylinders with said accumulator and 70 one another, said cylinder and piston being supported in spherical seats at the platform of the hangar and at the truck, and arms upon said intermediate members extending towards both sides beyond the running rails and upon 75 which the platform of the hangar is adapted to rest, and pivotally mounted roller or ball bearings at the end of said arms.

9. In a rotatable movable hangar for dirigibles, intermediate hydraulic members, consisting of a cylinder with reciprocating piston, inserted between the wheel truck and the supporting plate at the underside of the hangar platform, a hydraulic accumulator 80 (pressure equalizer) in which a constant pressure is maintained, and pipes for connecting all said cylinders with said accumulator and one another, said piston being supported in 85 a spherical seat at the truck and said cylinder being adapted to slide at the platform of the 90 hangar transversely to the direction of travel of the hangar, and arms upon said intermediate members extending towards both sides beyond the running rails and upon which the platform of the hangar is adapted to rest, and 95 pivotally mounted roller or ball bearings at the ends of said arms.

In testimony whereof I affix my signature.
OTTO KRELL.
